(57) **CLAIM**

The ornamental design for a display screen or portion thereof with a set of icons, as shown and described.

DESCRIPTION

FIG. 1 is a front view of an icon from the display screen or portion thereof with a set of icons, shown in isolation; FIG. 2 is a front view of another icon from the display screen or portion thereof with a set of icons, shown in isolation; FIG. 3 is a front view of another icon from the display screen or portion thereof with a set of icons, shown in isolation; FIG. 4 is a front view of another icon from the display screen or portion thereof with a set of icons, shown in isolation; and, FIG. 5 is a front view of another icon from the display screen or portion thereof with a set of icons, shown in isolation. The claimed design is directed to the collective appearance of the set of icons shown in FIGS. 1-5. The broken lines illustrate a display screen and form no part of the claimed design.

1 Claim, 3 Drawing Sheets
